ELECTRICAL RELAY

Clarence S. Snavely, Pittsburgh, Pa., assignor to
The Union Switch & Signal Company, Swiss-
vale, Pa., a corporation of Pennsylvania

Application April 28, 1937, Serial No. 139,535

7 Claims. (Cl. 200—93)

My invention relates to electrical relays, and particularly to polar relays for use in centralized traffic controlling systems for railroads such, for example, as that disclosed and claimed in an application for Letters Patent of the United States, Serial No. 31,592, filed by myself and others, on July 16, 1935, for Remote control systems.

One object of my invention is to provide a polar relay of simple, rugged, and compact construction which will operate without appreciable wear or change in operating characteristics over a long period of time, and for a very large number of operations.

Another object of my invention is to provide a quick acting polar relay in which the inertia of the armature is reduced to a minimum, and in which improper operation due to overenergization of the relay is prevented.

A further object of my invention is to provide a reliable polar relay which is inexpensive to manufacture.

Further objects and characteristic features of my invention will appear as the description proceeds.

I shall describe one form of relay embodying my invention, and shall then point out the novel features thereof in claims.

In the accompanying drawings, Figs. 1 and 2 are front and rear elevational views showing one form of relay embodying my invention, the front and rear cover plates of the relay being removed to better illustrate the construction of the operating parts. Fig. 3 is a vertical sectional view of the relay shown in Fig. 1. Fig. 4 is a sectional view taken on the line IV—IV of Fig. 1. Fig. 5 is a detail view of the armature of the relay together with the insulating member which supports it and the flexible contact fingers of the relay. Fig. 6 is a top plan view of the insulating spool 25 and associated coil 26 comprising part of the operating winding of the relay.

Similar reference characters refer to similar parts in each of the several views.

Referring to the drawings, the relay in the form here shown comprises a rectangular frame 1 of insulating material that can be readily moulded, such for example, as a phenol condensation product, which frame supports all of the operating parts of the relay. Provided on the frame 1 at its upper end are a pair of depending lugs 2 and 3 having threaded inserts 2^a and 3^a moulded therein, and provided on the frame 1 at its lower end are a pair of upstanding lugs 4 and 5 similar to the lugs 2 and 3, which latter lugs have threaded inserts 4^a and 5^a moulded

therein. A U-shaped yoke 6 of magnetizable material is clamped against the rear faces of the lugs 2 and 4 by means of screws 7 which pass through clearance holes in the legs 6^a and 6^b of the yoke 6 and are screwed into the inserts 2^a and 4^a, and a similar yoke 8 is clamped against the rear faces of the lugs 3 and 5 by means of screws 9 which pass through clearance holes in the legs 8^a and 8^b of this latter yoke and are screwed into the inserts 3^a and 5^a. The yokes 6 and 8 are disposed with their upper and lower legs in spaced confronting relation, and have their ends ground, chromium-plated, and polished for a purpose which will appear hereinafter. The yokes 6 and 8 are constantly magnetized by means of a pair of U-shaped permanent magnets 10 and 11 having ground ends which engage the yokes at their rear sides. The permanent magnets 10 and 11 are held in place in a manner which will be described more fully hereinafter.

The frame 1 is further provided at its medial portion in a vertical direction, as viewed in Figs. 1 and 2 with a pair of inwardly extending lugs 13 and 14 having moulded in their opposite sides 25 threaded inserts 13^a, 13^b, and 14^a, 14^b, respectively. A front pivot support 15, having a fixed front pivot 16 riveted thereto, is secured to the lugs 13 and 14 at their forward sides by means of screws 17 screwed into the inserts 13^a and 14^a, and a rear pivot support 18 having an adjustable rear pivot 19 mounted therein is secured to the lugs 13 and 14 at their rear sides by means of screws 20 screwed into the inserts 13^b and 14^b. The rear pivot 19 is screwed through a threaded hole 21 provided in the rear pivot support in horizontal alignment with the front pivot 16, and is arranged to be locked in an adjusted position by means of a lock nut 22.

Pivotedly mounted on the front and rear pivots 16 and 19 is a member 23 of insulating material that can be readily moulded, and moulded into this member adjacent the rear end thereof is an armature 24 of suitable magnetizable material, 45 such for example, as silicon steel. The upper and lower ends of the armature 24 extend between, and cooperate with, the confronting ends of the upper and lower legs of the magnetizable yokes 6 and 8 in such manner that the armature 50 is free to swing between a normal extreme position in which the upper end of the armature engages the chromium-plated end of the leg 6^a of the yoke 6, and the lower end of the armature engages the chromium-plated end of the leg 8^b 55

of the yoke 8, and a reverse extreme position in which the upper end of the armature engages the chromium-plated end of the leg 8^a of the yoke 8, and the lower end of the armature engages the 5 chromium-plated end of the leg 6^b of the yoke 6. To improve the magnetic efficiency of the relay and prevent wear, the ends of the armature are tapered in such manner that when the armature is swung to either extreme position, the engaging 10 portions of the armature and the yokes will be disposed in flat surface relation, and the tapered surfaces of the armature are chromium-plated.

A hollow spool 25 having a coil 26 wound thereon surrounds the upper end of the armature, and a similar spool 27 having a coil 28 wound thereon surrounds the lower end of the armature. The spool 25 is held in the proper vertical position by means of the lugs 2 and 3 and the lugs 13 and 20 14, and in the proper horizontal position by means of notches 25^a (see Fig. 6) which receive the yokes 6 and 8. The spool 27 is similarly held in the proper vertical position by means of the lugs 4 and 5 and the lugs 13 and 14, and in the proper 25 horizontal position by means of notches which receive the yokes 6 and 8. The leads 26^a and 26^b of the coil 26 are soldered to the inner ends of coil connectors 29^a and 29^b which are moulded into the opposite sides of the frame 1, and the 30 leads 27^a and 27^b of the coil 27 are soldered to the inner ends of coil connectors 30^a and 30^b which are likewise moulded into the opposite sides of the frame 1. The coil connectors 29^a, 29^b, 30^a, and 30^b project through the outer side of the 35 frame 1 far enough to permit external circuit connections to be readily soldered to their outer ends. In practice, the coils 26 and 28 will usually be connected in series in an operating circuit which is at times supplied with current of normal polarity, and at other times with current of reverse polarity, and together constitute the operating winding of the relay. The coils 26 and 27 may, however, if operating conditions require, be included in separate circuits, as will be readily 40 understood.

The forward end of the insulating member 23 is provided with an enlarged portion 23^a, and moulded into this enlarged portion are four flexible contact fingers 35, 36, 37, and 38. Each of 45 these fingers has a long end and a short end projecting out of the insulating member in parallel spaced relation, and the short ends of the fingers are connected by means of flexible leads 39, 40, 41, and 42 with circuit connectors 43, 44, 45 and 46, respectively, which are moulded into the frame 1 above and below, as the case may be, the coil connectors 29^b, 29^a, 30^a, and 30^b, and which connectors project through the sides of the frame 1 to permit external circuit wires to be soldered 50 directly thereto. The long ends of the fingers extend toward the four corners of a rectangle, and cooperate at their outer ends with fixed normal contact members 35^a, 36^a, 37^a, and 38^a and fixed reverse contact members 35^b, 36^b, 37^b, and 38^b, respectively, which are moulded into the sides 55 of the frame 1 above and below the circuit connectors in a manner which will be readily apparent from an inspection of the drawings. The front and back contact members are each provided at their inner ends with a portion which is bent at an angle to the main part of the contact member in such manner that when the armature 24 is midway between its two extreme positions, the bent portion of each contact member will extend 60 parallel to the associated finger, and each 70 75

bent portion is provided with a pair of contact buttons 48 which cooperate with similar contact buttons 47 provided on the associated flexible contact finger to provide a low resistance contact. The outer ends of the fixed contact members extend through the side of the case in the same manner as the ends of the coil connectors and the circuit connectors to permit circuit wires to be readily soldered directly to these members. The parts are so proportioned that when the armature is midway between its normal and reverse 10 positions, the contact buttons 47 on each finger will be midway between the contact buttons 48 on the associated normal and reverse fixed contact members, but that when the armature is swung 15 to its normal extreme position, the contact buttons 47 on the contact fingers will then engage the contact buttons 48 on the fixed normal contact members to close normal contacts 35-35^a, 36-36^a, 37-37^a, and 38-38^a, and that when the 20 armature is swung to its reverse extreme position, the contact buttons 47 on the fingers will then engage the contact buttons 48 on the fixed reverse contact members to close reverse contacts 35-35^b, 36-36^b, 37-37^b, and 38-38^b. The parts 25 are further so proportioned that when the armature occupies either its normal or its reverse extreme position, the flexible contact fingers will be flexed a slight amount intermediate their ends, whereby an effective low resistance contact is 30 provided between the cooperating contact buttons.

The relay further comprises a back cover plate 50 of moulded insulating material, and a front cover plate 51 also of moulded insulating material. 35 These cover plates are clamped against the front and the rear sides, respectively, of the frame 1 by means of screws 52, and together with the frame form a case which encloses all of the operating parts of the relay. The screws 52 pass 40 through suitable clearance holes in the rear cover plate and in the frame and are screwed into threaded inserts provided in the front cover plate. The front cover plate is formed with a window 53 which is closed by a window pane 54, whereby all 45 of the parts of the relay can be readily inspected without the necessity for removing the cover plates. The back cover plate is provided with recesses 55 which receive the ends of spring clips 56, which clips, when the rear cover plate is fastened in place, engage the rear faces of the magnets to hold the magnets in the proper operative 50 relation with respect to the magnetic yokes.

Assuming that the left-hand ends of the permanent magnets 10 and 11, as viewed in Fig. 1, 55 are north poles and the opposite ends are south poles, both legs of the magnetic yoke 6 will become north poles while both legs of the magnetic yoke 8 will become south poles. Under these conditions, flux will flow from the yoke 6 to the yoke 8. This flux will distribute itself in the air gaps between the confronting ends of the legs of the yoke in such a way as to allow the greatest amount of flux to flow. That is to say, when the armature is swung to its normal extreme position in 60 which it is shown in the drawings, the greater part of the flux which passes from the yoke 6 to the yoke 8 will flow downwardly through the armature 24, but when the armature is swung to its reverse extreme position, the greater part of this 65 flux will then flow upwardly through the armature. It will be apparent, therefore, that both the amount and the direction of the polarizing flux which passes lengthwise through the armature depends upon the particular position of the 70 75 76

armature with respect to the confronting ends of the legs of the yokes 6 and 8. When the armature is midway between its two extreme positions, there is no polarizing flux through the armature 5 in the direction of its length because both ends of the armature are at the same magnetic potential, and under these conditions, all of the flux which passes from the yoke 6 to the yoke 8 will pass through the air gaps between the confronting 10 legs 6^a and 8^a and 6^b and 8^b.

When the operating winding of the relay is supplied with current, the upper end of the armature will become a north pole and the lower end of the armature will become a south pole, or vice 15 versa, according as the operating winding is then supplied with current of reverse polarity or with current of normal polarity. Assuming that the armature occupies its normal extreme position in which it is shown in the drawings and that the 20 operating winding is supplied with current of reverse polarity, the upper end of the armature will be repelled from the leg 6^a of the yoke 6 and will be attracted toward the leg 8^a of the yoke 8, and the lower end of the armature will be repelled 25 from the leg 8^b of the yoke 8 and will be attracted toward the leg 6^b of the yoke 6. As a result, the armature will quickly move from its normal position to its reverse position and will thereby open the 30 normal contacts of the relay and close the reverse contacts. As soon as the armature reaches its reverse position, the current can then be removed from the operating winding and the armature will then remain in its reverse position and will hold its reverse contacts closed, by virtue of 35 the polarizing flux passing through the armature, as will be readily understood.

If, when the armature occupies its reverse position, the operating winding is supplied with current of normal polarity, the upper end of the 40 armature will then be repelled from the leg 8^a of the yoke 8 and will be attracted toward the leg 6^a of the yoke 6, while the lower end of the armature will be repelled from the leg 6^b of the yoke 6 and will be attracted toward the leg 8^b of the yoke 45 8. The armature will therefore quickly move from its reverse position to its normal position and will thus open its reverse contacts and close its normal contacts. As soon as the armature has reached its normal position, the current may 50 again be removed from the operating winding and the armature will then remain in the position shown. If, when the armature occupies its normal position, current of normal polarity is supplied to the operating winding, or, if, when the 55 armature occupies its reverse position current of reverse polarity is supplied to the operating winding, the armature will be held in the position which it then occupies in a manner which will be readily understood without further detailed description.

With a relay constructed in the manner thus far described, it will be apparent that when the armature occupies its normal position and the operating winding is supplied with current of reverse polarity to cause the armature to move to its reverse position, the flux which is set up in the permanent magnets in the reverse direction from 60 their proper magnetization, and if the armature has sufficient inertia and the flux is of sufficient magnitude, two things may occur which will adversely affect the operation of the relay. If the flux in the permanent magnet actually becomes 65 reversed in direction before the armature reaches

its mid position, the armature will tend to return to its original position. That is to say, the relay will not pole as intended, and as a result a failure in the system which it controls will occur. If the magnetomotive force set up by the operating 5 winding is great enough, and if the permanent magnet is not properly designed, the degree of magnetization of the permanent magnet will become changed and will cause a resulting change 10 in the calibration of the relay. This same action 10 may occur when the armature of the relay occupies its reverse position and the operating winding of the relay is supplied with current of normal polarity. The failure of the armature to reverse in the proper manner is known as "locking" 15 and cannot occur in a relay embodying my invention for the following reasons. In the first place, the moment of inertia of the movable parts of the relay has been made small by reducing its weight and by pivoting it at its center of gravity, 20 so that a very small force is required to cause the armature to reverse. In the second place, the cross-sectional area of the armature has been made small enough so that the armature will saturate when normal operating potentials are placed 25 across the winding, thereby limiting the amount of flux which the operating winding can supply to the permanent magnet. In the third place, the demagnetizing effect of the operating winding 30 on the permanent magnet, as well as the demagnetizing effect due to external fields has been almost entirely eliminated by properly proportioning the dimensions of the permanent magnet, and by properly controlling the process by which the 35 magnet is heat treated and the process by which it is magnetized.

One advantage of a relay constructed in the manner described is that since the armature and associated moving parts of the relay are light in weight, the relay is capable of high speed operation.

Another advantage of a relay constructed in the manner described is that the relay will satisfactorily operate contacts capable of carrying relatively large currents in response to a relatively 45 small power input.

Another advantage of a relay constructed in the manner described is that it is possible to inspect all of the vital parts of the relay without removing the relay from service. Thus, if the 50 contacts become worn or pitted, or if they are bent out of shape, or if the magnetic gaps get out of adjustment, these facts may be detected by casual inspection and the relay removed from service. If circuit failures occur, the contacts 55 can be tested from the front of the relay.

A further advantage of a relay constructed in the manner described is that the parts of the relay are so constructed that very little adjustment of the contacts is required, and that, as a 60 result, contact failures due to warping are unlikely to occur.

A still further advantage of a relay constructed in the manner described is that due to the arrangement of the parts no forces are transmitted through bearing surfaces except any minor forces which might exist due to unbalances in the magnetic circuit and that due to the weight of the movable element. This very materially reduces 65 70 the wear on bearing surfaces.

Although I have herein shown and described only one form of relay embodying my invention, it is understood that various changes and modifications may be made therein within the scope 75

of the appended claims without departing from the spirit and scope of my invention.

Having thus described my invention, what I claim is:

- 5 said yokes for polarizing said relay, whereby said armature is magnetically biased to its nearest extreme position, a first spool surrounding one end of said armature and held in place longitudinally between the lugs of said first and third pairs and held in place laterally by notches formed therein which receive said yokes, a first coil wound on said first spool, a second spool surrounding the other end of said armature and held in place 10 longitudinally between the lugs of said second and third pairs and held in place laterally by notches formed therein which receive said yokes, a second coil wound on said second spool, and contacts operatively connected with said armature.
- 15 7. A relay comprising a rectangular frame of moulded insulating material, a first pair of inwardly extending lugs formed on one end of said frame, a second pair of inwardly extending lugs formed on the other end of said frame, a third 20 pair of inwardly extending lugs formed on said frame intermediate its ends, two U-shaped magnetizable yokes secured to the lugs of said first and second pairs with their legs in spaced confronting relation, front and back pivot supports 25 secured to the opposite sides of said third pair of lugs and provided with aligned pivots, a mem- ber of moulded insulating material pivotally mounted on said pivots, an armature moulded into said member and having its ends disposed between the confronting ends of said yokes for movement between normal and reverse positions, 5 a permanent magnet connected with said yokes for polarizing said relay, whereby said armature is magnetically biased to its nearest extreme position, a first spool surrounding one end of said armature and held in place longitudinally be- 10 tween the lugs of said first and third pairs and held in place laterally by notches formed therein which receive said yokes, a first coil wound on said first spool, a second spool surrounding the other end of said armature and held in place lon- 15 gitudinally between the lugs of said second and third pairs and held in place laterally by notches formed therein which receive said yokes, a second coil wound on said second spool, and contact fingers moulded into said insulating member and 20 cooperating at their free ends with fixed normal and reverse contact members moulded into said frame to form normal and reverse contacts which are closed according as said armature occupies its normal or its reverse position. 25

CLARENCE S. SNAVELY.
